E. H. JONES,
ELECTRODE FOR SOLDERING AND DEPOSITING METALS BY THE ELECTRIC ARC.
APPLICATION FILED AUG. 16, 1919.

1,341,647.

Patented June 1, 1920.

FIG. 1.

FIG. 3. FIG. 5. FIG. 8.

FIG. 2.

FIG. 4. FIG. 6. FIG. 7.

INVENTOR:

Ernest Henry Jones
By Wallace White
ATTY.

UNITED STATES PATENT OFFICE.

ERNEST HENRY JONES, OF ISLINGTON, LONDON, ENGLAND.

ELECTRODE FOR SOLDERING AND DEPOSITING METALS BY THE ELECTRIC ARC.

1,341,647.

Specification of Letters Patent.

Patented June 1, 1920.

Application filed August 16, 1919. Serial No. 317,981.

To all whom it may concern:

Be it known that I, ERNEST HENRY JONES, subject of the King of Great Britain, residing at Church street, Islington, London, England, have invented new and useful Improvements in Electrodes for Soldering and Depositing Metals by the Electric Arc, of which the following is a specification.

In the manufacture of electrodes for soldering and depositing metals by the electric arc, the metal wire is wound with asbestos yarn, which in practice occasionally becomes loose and unwinds. This invention has for its object improvements whereby this defect is remedied.

According to this invention, a mechanical attachment of the yarn to the wire is effected at both ends of the electrode.

The accompanying drawings illustrate several examples of mechanical attachment according to the invention. Figure 1 is an elevation and Fig. 2 is a plan showing one end of an electrode wire *a* formed with a saw cut *b* into which the end of the asbestos yarn *c* is forced and held.

Figs. 3 and 4 are similar views of one end of an electrode wire *a* formed with a wedge shaped slot *d* into which the end of the asbestos yarn *c* is forced and held.

Figs. 5 and 6 are also similar views of one end of an electrode wire *a* fitted with a ring or band clip *e* which is caused to grip the asbestos yarn *c* tightly to the wire *a*.

Fig. 7 is a modification of Figs. 5 and 6 in which the end of the wire *a* is tapered to receive a ring or band *f* of a diameter to grip the yarn *c* tightly to the wire *a* when the ring or band *f* is forced on the end of the wire.

Fig. 8 is a modification of Figs. 1 and 2 in which the saw cut or slot *h* is formed at a suitable angle in the side of the wire *a*.

It will be understood that other mechanical methods of securing the yarn to the wire may be adopted. For example, the slots *b*, *d* and *h* may be partly or wholly closed after the yarn *c* has been inserted; an eye or other opening may be employed instead of the slot, and one or more turns of wire or other material may be employed instead of the band clip *e*.

I claim:—

1. Electrodes for soldering and depositing metals by the electric arc, comprising a metal wire, asbestos yarn wound upon said wire, and mechanical fastenings for the ends of the asbestos yarn, as set forth.

2. Electrodes for soldering and depositing metals by the electric arc, comprising a metal wire formed with a slot in each end, asbestos yarn wound upon said wire and having its ends secured in the slots of said wire, as set forth.

In testimony whereof I have signed my name to this specification.

ERNEST HENRY JONES.
